US0D1022184S

(12) **United States Design Patent** (10) Patent No.: **US D1,022,184 S**
(45) Date of Patent: ** Apr. 9, 2024

(54) **DIVING MASK**

(71) Applicant: **SHENZHEN CP-LINK ELECTRONIC CO., LTD**, Shenzhen (CN)

(72) Inventors: **Chaowu Liao**, Yiyang (CN); **Wu Su**, Shenzhen (CN)

(73) Assignee: **SHENZHEN CP-LINK ELECTRONIC CO., LTD**, Shenzhen (CN)

(**) Term: **15 Years**

(21) Appl. No.: **29/849,123**

(22) Filed: **Aug. 8, 2022**

(51) LOC (14) Cl. **29-02**

(52) U.S. Cl. **D24/110.2**

(57) **CLAIM**

The ornamental design for a diving mask, as shown and described.

DESCRIPTION

FIG. 1 is a perspective view of a diving mask showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

and,

FIG. 12 is an enlarged view of portion 12 shown in FIG. 2.

The dash-dash broken lines in the drawings depict portions of the diving mask that form no part of the claimed design. The dot-dash broken lines represent boundaries of the enlarged portions and form no part of the claimed design.

1 Claim, 12 Drawing Sheets
